(57) **CLAIM**

I claim the ornamental design for a trailer yoke, as shown and described.

DESCRIPTION

FIG. 1 is a perspective view of a trailer yoke showing my new design;

FIG. 2 is a first side elevation view of the trailer yoke of FIG. 1;

FIG. 3 is a second side elevation view of the trailer yoke of FIG. 1;

FIG. 4 is an elevation anterior view of the trailer yoke of FIG. 1;

FIG. 5 is an elevation posterior view of the trailer yoke of FIG. 1;

FIG. 6 is a top plan view of the trailer yoke of FIG. 1; and FIG. 7 is a bottom plan view of the trailer yoke of FIG. 1. FIGS. 8-14 show a second embodiment of a trailer yoke showing my new design.

FIG. 8 is a perspective view of a trailer yoke showing my new design;

FIG. 9 is a first side elevation view of the trailer yoke of FIG. 8;

FIG. 10 is a second side elevation view of the trailer yoke of FIG. 8;

FIG. 11 is an elevation anterior view of the trailer yoke of FIG. 8;

FIG. 12 is an elevation posterior view of the trailer yoke of FIG. 8;

FIG. 13 is a top plan view of the trailer yoke of FIG. 8; and FIG. 14 is a bottom plan view of the trailer yoke of FIG. 8. FIGS. 15-21 show a second embodiment of a trailer yoke showing my new design.

FIG. 15 is a perspective view of a trailer yoke showing my new design;

FIG. 16 is a first side elevation view of the trailer yoke of FIG. 15;

FIG. 17 is a second side elevation view of the trailer yoke of FIG. 15;

FIG. 18 is an elevation anterior view of the trailer yoke of FIG. 15;

FIG. 19 is an elevation posterior view of the trailer yoke of FIG. 15;

(Continued)

FIG. 20 is a top plan view of the trailer yoke of FIG. 15; and, FIG. 21 is a bottom plan view of the trailer yoke of FIG. 15. The broken lines shown in FIGS. 1-21 are for the purpose of illustrating portions of the trailer yoke that form no part of the claimed design.

1 Claim, 21 Drawing Sheets
